No. 36,981.

Patented June 14, 1904.

UNITED STATES PATENT OFFICE.

PETER BELLISIO, OF COLUMBUS, OHIO, ASSIGNOR TO THE M. C. LILLEY & COMPANY, OF COLUMBUS, OHIO, A CORPORATION OF OHIO.

DESIGN FOR A ROBE.

SPECIFICATION forming part of Design No. 36,981, dated June 14, 1904.

Application filed May 5, 1904. Serial No. 206,594. Term of patent 14 years.

To all whom it may concern:

Be it known that I, PETER BELLISIO, a subject of the King of Italy, residing at Columbus, in the county of Franklin and State of Ohio, have invented a new, original, and ornamental Design for Robes, of which the following is a specification, reference being had to the accompanying drawings, forming a part thereof, in which—

of the robe, showing my new design. Fig. 2 is a perspective view of the back thereof.

What I claim as new, and desire to secure by Letters Patent, is—

The ornamental design for a robe as shown. 15

PETER BELLISIO.
